[57] CLAIM

The ornamental design for a cabinet top, as shown and described.

DESCRIPTION

FIG. 1 is a rear elevation of a cabinet top embodying the present invention.

FIG. 2 is a top plan view of the cabinet top of FIG. 1 with portions omitted for convenience of illustration.

FIG. 3 is a side elevation of the cabinet top illustrated in FIGS. 1 and 2 with portions omitted for convenience of illustration.

FIG. 4 is a bottom plan view of the cabinet top illustrated in FIGS. 1, 2 and 3 with portions omitted for convenience of illustration.

FIG. 5 is a front elevation of the cabinet top of FIGS. 1, 2, 3 and 4.

FIG. 6 is a perspective view of the cabinet top. The opposite side of the cabinet top from the side shown in FIG. 3 is the mirror image of the cabinet top shown in FIG. 3.
